TOWEL CABINET

Harry M. Lui, Detroit, Mich.

Application July 27, 1953, Serial No. 26,160

Term of patent 7 years

(Cl. D4—3)

To all whom it may concern:

Be it known that I, Harry M. Lui, a citizen of the United States, residing in the city of Detroit, county of Wayne, and State of Michigan, have invented a new, original, and ornamental Design for a Towel Cabinet, of which the following is a specification, reference being had to the accompanying drawing, forming part thereof, in which;

Fig. 1 is a front elevational view of a towel cabinet showing my new design;

Fig. 2 is a side elevation thereof; and

Fig. 3 is a perspective view of the towel cabinet showing my new design.

The rear is a substantially plane and flat surface and is not one of the dominant features of my design.

I claim:

The ornamental design for a towel cabinet, substantially as shown and described.
